UNITED STATES PATENT OFFICE.

CELTIC NICHOLSON, OF LEOMINSTER, MASSACHUSETTS.

DIPPING MACHINE.

Application filed March 2, 1927. Serial No. 172,120.

This invention relates to a machine particularly designed for dipping small articles in a bath of lacquer, enamel, or other coating material.

5 It is the general object of my invention to provide a machine for such purposes which will be reliable and effective in operation, and which will permit small articles to be dipped and coated with a substantial saving 10 of time and labor, as well as with marked economy in the use of coating material.

With this general object in view, one important feature of my invention relates to the provision of means for automatically 15 withdrawing the articles from the dipping solution at a predetermined slow rate of speed.

Another feature of my invention relates to the provision of means for lifting the articles to a predetermined raised position, and for retaining the articles in such position until manually removed therefrom. I have also provided convenient devices for supporting 20 the articles to be dipped, and for positioning them in groups in the dipping machine.

My invention further relates to arrangements and combinations of parts which will be hereinafter described and more particularly pointed out in the appended claims.

30 A preferred form of the invention is shown in the drawings, in which—

Fig. 1 is a front elevation of my improved dipping machine, with portions of the tank shown in section;

Fig. 2 is a sectional side elevation of the machine, taken along the line 2—2 in Fig. 1;

Fig. 3 is an enlarged front elevation, partly in section, of a portion of the driving mechanism;

Fig. 4 is a sectional bottom view, taken along the line 4—4, in Fig. 3;

Fig. 5 is a front elevation of certain of the parts shown in Fig. 3, but in a different position; and

Fig. 6 is a detail view of one of the work holding boards.

Referring to the drawings, my improved dipping machine comprises a frame having end members 10, upper cross bars 11, and rear braces 12. The frame members may be of

any convenient construction, but are preferably made from pieces of angle iron.

A tank 13 is provided for holding the lacquer, enamel, or other coating solution, and the tank is preferably mounted upon small 55 wheels or rolls 14, so that it may be easily moved to and from operative position. This provision of an easily removable tank is of considerable importance, as it enables the machine to be readily used for dipping articles in different kinds or colors of coating solutions by simply rolling one tank out of the machine and replacing the same with a tank having a different solution therein.

A dipping head 16 is guided for vertical 65 movement between the end frames 10 and is supported by ropes or cables 17 passing over guide pulleys 18 at the top of the frame, and having counter-weights 19 suspended from the free ends thereof. The frame 16 is thus 70 supported in such manner that it may be moved vertically by hand with relatively slight effort.

A threaded rod 20 is secured to the dipping head 16 near the center of its length and 75 extends upward through a plate or bushing 21 (Fig. 3) resting upon the cross bars 11 of the machine frame and secured thereto by bolts 22.

A driving member 23 is rotatably supported on the plate or bushing 21, and is provided with a bevel gear 24 engaged by a pinion 25 (Fig. 1) on a horizontal shaft 26. The shaft 26 is provided with a cone pulley 27 and is continuously rotated by a belt 28 85 from any convenient source of power (not shown).

The member 23 is provided with threaded portions 30 (Fig. 4) slidably mounted in a transverse guideway in the member 23 and 90 forming a split nut for the threaded rod 20. Studs 31 project downward from the sliding members 30 into cam slots 32 in a locking plate 33. The plate 33 has a limited angular movement relative to the member 23, and by 95 such movement the threaded members 30 are moved toward or away from the threaded rod 20.

A plurality of spokes or handles 35 extend 100 outward from the plate 33, and a latch 36

(Fig. 3) is pivotally mounted on the member 23 and is adapted to engage one of the handles 35, as shown in Fig. 5. When the member 23 and plate 33 are thus locked together, the cam slots 32 are in such position that the threaded members 30 engage the threaded rod 20 and act as a nut therefor.

Coil springs 38 are each connected at one end to screws 39 in the plate 33, and at the other end to screws 40 in the member 23. When the latch 36 is raised, the springs 38 move the plate 33 angularly to release the split nut from the threaded rod 20.

In order to release the latch 36 automatically, I have provided a knock-off finger 42 (Fig. 1) which may be clamped in any desired vertical position on the threaded rod 20. When the rod is raised to a predetermined position, the finger 42 engages the depending portion 43 of the latch 36 and moves it from the position shown in Fig. 5 to that shown in Fig. 3, thus releasing the split nut and stopping the lifting operation. The dipping head 16 will remain in any position to which it has been moved, being retained by friction and by the effect of counter-weights 19.

By the mechanism thus far described, I have provided a dipping head which may be lowered manually to immerse articles in a coating solution and which may be raised automatically at a predetermined rate of speed to a selected elevation, at which point the lifting mechanism will be automatically disconnected.

While the machine is capable of general application, it is largely used for the dipping of small articles of wood, such as handles and knobs, and when used for such purposes, I preferably provide work-holding boards 45, one of which is shown in Fig. 6. Each board 45 is provided with a large number of nails 46 or other sharp pointed elements 46, extending through the board and spaced apart in two directions, so that a large number of articles W may be readily secured to each board by driving the articles against the ends of the nails 46 by a rubber hammer or some similar device. In actual practice, each board is usually adapted to support one hundred separate articles.

For attaching the boards 45 to the dipping head 16, I preferably provide holders 50, secured to the lower ends of rods 51, each of which is vertically adjustable in a sleeve or bearing 52 on the head 16.

On its lower face, each holder 50 is provided with inturned flanged members 53, between which the boards 45 may be longitudinally inserted. The provision of the adjustable rods 51 permits the machine to support different boards at different elevations, if desired, so that articles of different lengths may be dipped at a single operation by ad-

justing each rod 51 to correspond to the length 65 of the article supported thereby.

Having thus described my invention, it is believed that the operation and advantages thereof will be readily apparent. The operator first provides a tank 13 containing 70 lacquer, enamel, or other coating solution of the desired kind and color, and then assembles the pieces of work W on boards 45 and inserts the boards 45 in the holders 50, which have been vertically adjusted to the desired 75 relative heights. He then sets the knock-off finger 42 to engage the latch 36 at the desired elevation, and then depresses the dipping head 16 manually so that the articles are all immersed in the solution. He then grasps 80 one of the slowly rotating handles 35, and swings it to position to be locked by the latch 36, thus closing the lock-nut and placing the elevating mechanism in operation.

The head then proceeds to move upward 85 with a slow and uniform motion, and it is the provision of this slow and uniform withdrawal of the article from the coating solution which is one of the greatest advantages of 90 my invention, as articles thus slowly and uniformly withdrawn are very evenly coated. By suitably regulating the speed to the thickness of the coating solution, all parts of the articles may be smoothly coated with a minimum of material.

By the time the dipping head 16 has reached its selected elevation and its movement has ceased, the coating material will have drained from the articles to such an extent that the boards 45 may be removed and 100 quickly inverted, thus causing the remaining drop of material at the bottom of each article to spread out and smoothly coat the extreme end of the article. The work may be left on the boards in inverted position until 105 thoroughly dried, after which it may be readily removed therefrom.

In actual operation, the saving of lacquer or other coating material by the slow gradual withdrawal, permitting the solution to drip 110 back into the tank, has been found so great that the machines are quickly paid for by the saving in coating material alone, regardless of the great saving in time and labor. A further substantial saving is obtained by the 115 reduction in the amount of thinner which is used in the solution. This thinner is expensive and it adds nothing to the finished product, as it evaporates in the drying process. The reduced amount of thinner necessary for 120 use with my machine is thus a clear additional gain.

Having thus described my invention and the advantages thereof, I do not wish to be limited to the details herein disclosed, otherwise than as set forth in the claims.

What I claim is:

1. A dipping machine comprising means

to hold and immerse the work in a coating solution, means for withdrawing the work upwardly from said coating solution at a predetermined and relatively slow rate of travel, driving means for said work holder, said withdrawing means including a manually operable mechanism adapted to connect the driving means to raise the dipping head and an automatic mechanism to thereafter disconnect the driving means from the head.

5 2. A dipping machine comprising means to hold the work, mechanism for driving said means, and means permitting movement of the holding means irrespective of said mechanism, said holding means being movable freely downward to immerse the work in a coating solution, means to raise the work out of said coating solution at a definite predetermined and relatively slow rate of speed, 10 and means to vary said rate of speed.

15 3. A dipping machine comprising a tank, a work holder, mechanism for driving said work holder, means permitting movement of said work holder irrespective of said mechanism to immerse the work in the contents of the tank, means including said mechanism to raise the work holder at a predetermined regular rate of upward travel, and means to removably mount said work holder in the 20 machine.

25 4. A dipping machine comprising a tank, a work holder, mechanism for driving said work holder, means permitting movement of said work holder irrespective of said mechanism to immerse the work in the contents of the tank, means to raise the work holder at a predetermined regular rate of upward travel, and means to stop the movement of said 30 holder at any predetermined point, in its upward travel.

35 5. A dipping machine comprising a frame, a tank, a dipping head supported in said frame above said tank, mechanism for driving said dipping head, means permitting movement of said head irrespective of said mechanism, means to suspend the work from said head, said head being movable downward to dip the work, mechanical means to raise said frame and head at a slow predetermined rate of travel, and variable means to limit 40 said upward travel.

45 6. A dipping machine comprising a frame, a tank, a dipping head supported in said frame above said tank, means to suspend the work from said head, said head being movable downward to dip the work, a threaded rod secured to said head and extending upward therefrom, a split nut for said rod, means to rotate said nut continuously in a 50 definite vertical position, means by which said nut may be closed manually on said rod, and means to open said nut when said head has reached a predetermined elevation.

60 65 7. A dipping machine comprising a frame, a tank, a dipping head supported in said

frame above said tank, means to suspend the work from said head, said head being movable manually downward to dip the work, a continuously actuated driving member in said frame, manually operable means to connect 70 said driving member to raise said dipping head at a predetermined rate of travel, and adjustable automatic means to thereafter disconnect said driving member from said head, at a predetermined point in the travel of 75 said head.

8. A dipping machine comprising a frame, a tank, a dipping head supported in said frame above said tank, means to suspend the work from said head, said head being movable 80 manually downward to dip the work, a continuously actuated driving member in said frame, manually operable means to connect said driving member to raise said dipping head at a predetermined rate of travel, and 85 automatic means to disconnect said driving member from said head when said head has been raised to a predetermined elevation.

9. A dipping machine comprising a work holder, mechanism for driving said work holder, means permitting movement of said work holder irrespective of said mechanism, said means being adapted to move said work holder vertically in a predetermined path, 90 and a tank for the coating solution, said tank 95 being movably mounted for convenient horizontal insertion and removal in the machine beneath said work holder.

10. In a dipping machine, a dipping head, 100 a plurality of work holding devices, means in said head to detachably secure each of said devices to said head, and means for adjusting said securing means in said head, thereby to separately adjust the vertical position of each work holding device relative to said 105 head.

11. A dipping machine, comprising a frame, a dipping head and work supporting means removably held therein, to hold and immerse the work in a coating solution, a 110 threaded member on said frame, a rod, fixed to said head and in threaded engagement with said threaded member, means to rotate said threaded member thereby to actuate said rod and head toward and from said coating solution, means to stop the movement of said rod and head at a predetermined point in the travel thereof, and means to predetermine the rate of travel of said rod and head.

12. In a dipping machine, a dipping head, 120 a plurality of work holding devices comprising boards removably mounted on said head, and pointed holding devices fixed in spaced relation in said boards and on which articles to be coated may be readily positioned and affixed, and means for separately adjusting the vertical position of each of said boards relative to said head.

13. A dipping machine, comprising a 130 frame, a tank, a dipping head supported in

said frame above said tank, means to suspend the work from said head, said head being movable manually downward to dip the work, a continuously actuated driving member in said frame, a threaded rod mounted on said head, means in said driving member adapted for engagement with said rod, manually operable means to place said engageable means in threaded engagement with said rod thereby

to connect said rod to said driving means and 10 automatic means to thereafter disconnect said engageable means from said rod at a predetermined point in the travel of said head.

In testimony whereof I have hereunto af- 15 fixed my signature.

CELTIC NICHOLSON.
